UNITED STATES PATENT OFFICE.

NORTON A. NEWDICK, OF COLUMBUS, OHIO, ASSIGNEE TO THE COLODER COMPANY, OF COLUMBUS, OHIO, A CORPORATION OF DELAWARE.

LOADING MACHINE.

Application filed December 11, 1922. Serial No. 606,236.

This invention relates to improvements in loading machines and has for its primary object the provision of an improved and simplified machine adapted for successful use for loading loose broken down or blasted minerals into suitable carriers for transportation from the mine, and to provide a machine so constructed as to be capable of operating efficiently into winding and tortuous passageways of underground mines, particularly coal mines.

In accordance with the invention there is provided a loading machine which consists preferably of a wheeled truck adapted for movement over a mine track-way, and upon which truck is mounted for pivotal or swinging movement in both horizontal and vertical planes the inclined elongated frame of a gathering conveyor, the said frame being constructed so that its rear or discharge end is vertically pivoted above the truck, and its forward end arranged for sweeping engagement with the ground or floor of a mine at positions in advance of the truck, the arrangement of parts being such that the gathering conveyor may swing from a fixed pivotal position upon a portable base unit across the width of a mine room or corridor, and yet its rear or discharge end is maintainable in a relatively fixed position so that the conveying mechanism mounted upon a frame will be enabled to discharge the materials handled thereby into the movable material conveying pit cars placed at intervals to the rear of the machine.

One of the principal objects of the invention rests in the provision of a loading machine of the character aforesaid when the gathering conveyor consists of an endless conveying belt provided with spaced laterally extending flights, having the going and return ends thereof disposed in similar elevations and wherein the belt is driven by a pair of laterally spaced sprockets carried by the rear or discharge end of the frame, whereby the length of the belt between said sprockets moves in a substantially straight line transversely of said frame across the rear end thereof, the said frame being provided at this point with an open flight space across which the flights between said sprockets pass linearly, the construction being such that the belt, while discharging materials, is moving at a retarded or normal rate of travel, permitting the material to

fall by gravity through the open flight space into the pit cars placed therebeneath and in a controlled manner in which spilling or wasting of the coal is avoided.

Another object of the invention resides in the provision of a loading machine having a single plane conveyor belt so constructed and mounted for operation that the materials gathered thereby will be released from co-operation with the belt while the latter is traveling at a normal rate of speed.

A further object of the invention rests in the provision of a loading machine having a single plane conveyor belt so constructed that materials will be released from the belt during linear travel of the latter.

With these and other objects in view that will appear as the description proceeds, the invention consists in the novel features of construction, combination of elements and arrangements of parts, hereinafter more fully described and pointed out in the appended claims.

In said drawings:

Figure 1 is a top plan view of a loading machine constructed in accordance with the features of the invention.

Figure 2 is a side elevation of the machine.

Figure 3 is a vertical transverse sectional view taken on the plane indicated by the line 3—3 of Figure 2 and looking in the direction indicated by the arrows.

Figure 4 is a similar view on the line 4—4 of Figure 2.

Figure 5 is an enlarged detail view disclosing the thrust relation between the frame of the conveyor and the truck frame.

Figure 6 is a vertical sectional view taken through one of the drive sprockets of the gathering conveyor belt on the plane indicated by the line 6—6 of Figure 1.

Figure 7 is a detailed vertical sectional view taken on the line 7—7 of Figure 1 and disclosing the vertical pivotal mounting for the gathering conveyor frame.

Figure 8 is an enlarged vertical sectional view between the saddle journal and the conveyor frame.

Figure 9 is a vertical sectional view taken on the plane indicated by the line 9—9 of Figure 1.

Figure 10 is a transverse vertical sectional view taken on the line 10—10 of Figure 1.

Referring more particularly to the details of the invention, the numeral 1 indicates a

loading machine comprising the present invention in its entirety. This machine consists essentially of a portable base unit, in this instance in the form of a wheeled truck 2, upon which is pivotally mounted for swinging movement in both vertical and horizontal planes a gathering or loading conveyor 3. I preferably provide the wheeled truck 2 in lieu of the endless belt tractor type of truck because of the fact that the former has the ability of being rapidly transported from place to place in a mine, whereas the tractor type of truck is essentially slow, cumbersome and awkward to move and involves, therefore, a considerable loss of time while the machine is being moved from one working place to another. The tractor type of truck has the advantage, however, of being able to operate at any position within a mine, that is, it is not dependent upon a fixed course of travel, such a track. It is for this reason that the tractor type of loading machine can attack the material to be gathered from any angle with respect to the fixed longitudinal center line of a line, or at any angle with respect to a mine or pit car into which the loading machine is adapted to discharge materials. However, by the present construction the lack of portability or adjustability of the truck at the working face of a mine is compensated for by pivotally mounting the conveyor 3 upon the truck, so that said conveyor will be enabled to reach the farthest-most corners of a mine room by a swinging horizontal sweep movement, which movement is permitted to take place independently of the truck.

The truck 2 consists of a frame 4 having journalized therein transversely extending axles 5, upon which are mounted ordinary flanged track engaging wheels 6, arranged for co-operation with the track-way 7, the ends of the axles 5 being mounted in resilient journals 8 carried in connection with the sides of the frame 4.

Extending longitudinally between the axles 5 is a motor bed 9, which carries in this instance an electric motor 10 of appropriate horse power, which motor is employed to impart a slow powerful forward movement to the truck when the loading machine is in operation, or to effect what is known in the art as a "sump" movement, by means of which the conveyor 3 of the loading machine is forced positively into and under the materials to be loaded. To obtain this necessary powerful infeeding movement, the armature shaft of the motor 10 is equipped, as shown in Figure 4, with a pinion 11, meshing with an enlarged reduction gear 12 carried upon a short longitudinally extending shaft 13, which is journaled in bearings 14 carried in conjunction with the field frame of the motor 10. The

extreme forward end of the shaft 13 is equipped with a worm 15, in mesh with a worm gear 16 fixed upon the forward axle 5. By this arrangement of gearing it will be seen that the speed of the motor 10 may be suitably stepped down so that a slow powerful forward movement of requisite torque will be imparted to the wheels 6. The axles 5 impart power one to the other by means of the chain 17, which passes over suitable sprockets 18 provided at registering end of the axles 5.

The conveyor 3 consists in this instance of an elongated inclined frame 19, preferably formed from structural sheet metal, suitably ribbed and reinforced to possess strength, rigidity and durability. Generally, this frame includes a floor engaging or nose end 20, arranged in advance of the truck 2, a horizontally extending relatively elevated discharge end 21 and an inclined, intermediate connecting portion 22, arranged between the portions 20 and 21, and operative to raise the materials to be gathered to a suitable elevation for discharge into underlying pit cars 23, which are replaced as rapidly as they are filled by the operation of the machine.

To mount the frame 19, the truck 2 is provided with a pair of bearing 24, which support the transversely extending horizontally disposed trunnion shaft 25, upon which is pivotally mounted for swinging movement in a vertical plane a saddle journal 26. The yoke shaped end 27 of the journal is mounted as at 28 upon the shaft 25, so that the journal may swing bodily vertically. The said journal further includes a flat rearwardly extending portion 29, disposed immediately beneath the discharge end 21 of the frame 19, and the extreme rear end of the portion 29 is formed with a vertical socket 30, arranged for the reception of a stud 21 rigidly mounted upon and depending from the extreme rear end of the frame 19, the said stud constituting a vertical pivot or axis about which the frame 19 swings in a horizontal plane. By this construction it will be noted that the shaft 25 constitutes a horizontal pivot, enabling the frame 19 to swing in a vertical plane, so that the floor engaging end 20 of said frame may automatically accommodate itself to any irregularities or unevenness existing in the mine floor over which the said nose end of the machine sweeps.

To facilitate the horizontal movement of the frame, the journal 26 is formed with a forwardly projecting shelf 32, disclosed more particularly in Figure 3, which shelf carries a plurality of brackets 33 in which are supported for rotation rollers or other anti-friction members 34. These rollers are so disposed that the upper peripheries thereof engage with the machined under surface of a guard member 35 placed transversely

across the under surface of the frame 19. By this construction the rearwardly extending arm of the journal 26 is relieved of the burden of supporting the full weight of the frame 19, such weight being transferred mainly to the rollers 34, which permit the said frame to swing horizontally with but a minimum of resistance from its supporting structure. The guard member 35 is also provided with a lip 36 arranged to be received within an arcuate recess 37 provided in connection with the journal 26, the said lip serving to prevent the frame 19 from moving into a vertical plane independently of the supporting journal 26.

The conveyor 3 is formed to include an endless reversible conveyor belt 38, which has its going and return runs disposed to travel in similar elevations, wherein said belt is so mounted as to move in a substantially triangular course, the apex of said course being situated at the nose end of the machine and the base course thereof disposed at the rear or discharge end thereof. This belt may be of any suitable construction, but in the present instance consists of a plurality of roller carrying blocks 39, to which are attached or integrally formed flights or conveying arms 40, which project laterally from the line of advance or travel of the belt as a whole. It will be observed, by reference to Figure 1, that the blocks 39 are united by chain links 41, which impart flexibility to the belt and enables the latter to flex in both horizontal and vertical planes, adapting the belt to travel around the circumference of the sprockets and also to conform to the construction of the frame 19.

The belt 41 is arranged for travel in a pair of rearwardly diverging guides 42 carried by the frame 19, and situated at the rear ends of said guides and in suitable registration therewith is a pair of transversely spaced drive sprockets 43, around which the belt 38 travels and is driven.

The specific construction of each of the sprockets 43 is disclosed in Figure 6, by reference to which figure it will be observed that the frame 19 is formed to include for each sprocket a base plate 44, upon which arises a stud shaft 45 having disposed thereabout a bushing 46. Between the plate 44 and the under side of each of the sprockets 43 there is disposed a wear plate 47 and a thrust bearing 48, the plate 47 being provided with an upstanding oil ring 49. By this construction each of the sprockets 43 rotates freely around the axially disposed fixed shafts 45.

Suitably connected with each of the sprockets 43 for rotation therewith is a worm gear 50, arranged for rotation in dust proof oil containing casings 51 and disposed to mesh with the teeth of worms 52, also

mounted for rotation in their respective casings 51. The worms 52 are fixed for rotation in connection with the horizontally extending drive shaft 53, which carries a sprocket 54, over which is trained an endless chain 55 leading to a sprocket 56 mounted upon the driven member 57 of a disc clutch 58, the specific construction of which latter has been disclosed in Figure 10. The driving member 59 of the clutch is formed to include a bevel gear 60 arranged to mesh with a bevel tooth pinion 61, provided upon the armature shaft of an electric motor 62, which is of the reversible type, so as to be capable of reversing the direction of movement of the belt 38, enabling the latter to advance materials selectively through the spaced material conveying ways 63 of the machine, which are alternately available for the passage of material through the machine in the line of draft of the latter.

The disc clutch 58 includes an axial support 64, upon which is mounted the driven member 57 and the driving member 59. The driving member carries an end wall 65, upon which is mounted a plurality of pivoted bell cranks 66, carrying rollers 67 which are arranged to engage with a pressure plate 68 movable axially of the support 64 into frictional engagement with discs 69, these discs being alternately keyed to the driven and driving members 57 and 59 respectively of the clutch. The bell cranks are actuated through the medium of a sliding hub 70, suitably actuated either manually or automatically, wherein the arrangement is such that upon the forcing of the hub 70 inwardly of the clutch, the bell cranks will be simultaneously rocked to impart pressure to the disc 69, which serve to frictionally transmit the rotary movement of the driving member to the driven member. Furthermore, the clutch serves in the capacity of a slip element in the line of motion transmission of the conveyor. In the event that the belt 38 should engage with a relatively immovable wall or coal lump, damage to the driving elements of the conveyor will be avoided by the slip in the clutch 58, which may be set to slip under predetermined loads and in this respect serves to prevent careless or unskilled operators from injuring or breaking the machine.

One of the outstanding features of this construction resides in the sprockets 43 at the rear end of the frame 19. It will be observed that the present invention materially departs from the principles of analogous machines by the inclusion of the twin sprockets in lieu of a single sprocket, (a construction commonly found in machines of the prior art). Experience has demonstrated that the side arm single plane type of conveyor is extremely efficient in the gathering of coal, but at the same time it has been a difficult en-

engineering problem to provide an efficient method of enabling the coal or other materials loaded by a conveyor of this type to be properly released and elevated from the discharge end of the machine. It has been common practice to provide a single sprocket at the discharge end of the conveyor, but this construction causes the flights to travel in an arcuate path and upon passing around the circumference of the sprocket the speed of the flights is materially increased, and since the discharge of the materials has usually taken place during this arcuate movement from the flights, considerable difficulty has therefore resulted in properly controlling and directing the materials into the appropriately placed underlying carriers.

To overcome this centrifugal discharge of the materials from the gathering conveyor, recourse has been had usually to secondary or delivery conveyors including elevated hopper sides extending above the plane of delivery of the gathering conveyor or in laterally projecting wings or other structures placed at the rear end of the conveyor for overcoming the tendency of the conveying belt to scatter centrifugally coal discharged therefrom. By the present invention these structures are eliminated and efficient results obtained by cutting away the rear end of the frame 19 at 71 to provide an open flight space at positions in registration with the linear line of travel of the belt 38 between the twin driving sprockets 43. By this construction it will be observed that when coal or other materials are released from the conveying belt the latter is traveling at a relatively slow or normal rate of speed in which the coal is given ample opportunity to drop by gravity through the space 71 into the pit car disposed therebeneath. By this construction there is no whipping or centrifugal throwing of the coal, but simply a sharp positive vertical drop into the car beneath. Moreover, it will be observed that by the twin sprockets the flights move before the material is discharged therefrom through but 90 degrees of arcuate travel, in contracts to the possible 180 degrees of travel provided by the single sprocket construction. Therefore, by this construction I am enabled to combine the gathering advantages of a single plane conveyor together with the discharge advantages of a two plane conveyor in a single construction.

To effect bodily horizontal sweep movement of the conveyor I provide a side swinging mechanism which consists of a motor 72, of a reversible electric type, upon the armature shaft of which is mounted a pinion 73, meshing with a reduction gear 74, carried by a worm shaft 75. This shaft is journaled in connection with the frame of the motor 72 and extends parallel with the arma-

ture shaft of said motor. The shaft 75 is equipped with a worm 76, arranged to mesh with a worm gear 77 fixed upon a drum shaft 78, the latter being journaled for rotation between bearings 79 employed in connection with the support of the motor 72. Rotatable with the shaft 78 is a drum 80, in this instance in the form of a pocket sheave which is journaled for rotation in a vertical plane and around which is trained an ordinary anchor chain 81. The opposite links of this chain pass through hawse guides 82, fixed to the forward part of the frame 19, and the extreme outer ends of the chain 81 are adapted to be connected with suitably disposed laterally placed anchors, whereby upon the rotation of the drum or sheave 80 horizontal motion will be imparted to the frame 19 in accordance with the direction of rotation of the motor 72. This construction enables the front end of the machine to oscillate back and forth across the floor of a mine and to be continually maintained in engagement with the materials being gathered, so that the sweeping gathering arms or flights 40 of the belt 38 will be enabled to reach into and penetrate the body of materials to be gathered, causing the materials to be advanced in the line of draft of the machine, through either of the available ways 63, and finally discharged from the machine through the flight space 71.

During the gathering operations the machine is intermittently forced forwardly by the operation of the truck motor 10, which is operated to thrust the nose end 20 of the frame 19 into and beneath the materials to be loaded, assisting the functioning of the chain or belt 38. To secure this result and avoid strain on the swinging saddle journal 26, I provide the under part of the frame 19 at the forward end thereof with a centrally disposed arcuate shoe 83, disclosed particularly in Figure 5. This shoe is carried stationarily by the under part of the frame 19 and has the machined face 84 thereof disposed in engagement with rollers 85 disposed angularly to the vertical in the forward end of the truck 4. By this construction it will be observed that when the frame 19 is being thrust into engagement with the loose materials, the thrust strains occur largely through the truck frame 4, the shoe 83 and thence directly to the nose end of the machine, and are not transmitted in any direct manner to the saddle journal 26 and co-operating parts. It will be understood that the face 84 is struck on an arc confronting to the axis of the shaft 25, so that the presence of the shoe 83 will not interfere in any manner with the vertical swinging movements of the frame 19 when the latter is accommodating itself to floor irregularities or to the elevated positions

which the said frame assumes in being transported about the mine.

To facilitate the raising of the nose end of the frame 19 from off of the floor of a mine, into a position clear of the trackway over which the machine operates, I provide the truck frame with a hydraulic pump 86, disclosed more particularly in Figures 2 and 3. The upwardly and vertically moving piston 87 of the pump is provided with a transverse cross bar 88, to which are connected the ends of a pair of ordinary chains 89. These chains pass around guides or sheaves 90 and have their upper ends connected as at 91 with an equalizing link 92, carried in conjunction with the rearwardly extending end 29 of the journal 26. It will be understood that by the manipulation of the operating lever 23 of the pump, the piston 87 of the latter may be suitably elevated to impart a downward pull to the rear end of the conveyor 3, causing the latter to rock bodily about its horizontal fulcrum 25, and thereby lifting the forward nose end 25 of the frame to a position free of track interference.

From the foregoing description, taken in connection with the accompanying sheets of drawings, it will be seen that the present invention provides a loading machine of substantial, durable and simple design, so constructed as to withstand the severe service and inexperienced handling incident to the use of machinery in coal mines. The machine is controlled to a very large extent by the controllers for the motors 10, 62 and 72, eliminating manual adjustments and operations, thereby safeguarding the machine by preventing the negligence of the operators thereof from affecting the machine.

It will be noted that the machine consists of but one conveyor mounted upon but a single truck. In this particular the machine eliminates the use of a plurality of conveyors, or a plurality of trucks and without in any way sacrificing or lowering the efficiency of the machine as compared with the more complicated structures.

The machine may be well manipulated by but two operators, one of whom is called upon to operate the controllers for the various motors, and the other at the front end of the machine for the purpose of erecting the side feed jacks to which the ends of the chain 81 are connected. The motor 62 is

placed upon the inclined portion of the frame 19 so that the said motor will not interfere with or require greater head room for the machine than the frame 19 itself. It will be appreciated, of course, that the said motor 62 may be shifted into close proximity to the sprockets 43 when the machine is used to operate in coal mines having wide or thick seams. When the head room is restricted, however, I prefer to mount the motor as shown.

What is claimed is:

1. In a loading machine, a portable support, an elongated inclined conveyor frame, a vertical pivotal connection between the rear end of said frame and said support, permitting the front end of said frame to sweep horizontally in advance of said support, an endless conveyor belt having its going and return runs disposed at similar elevations, arranged for travel upon said frame, guides carried by said frame and disposed so that the discharge end of said belt moves in a linear course transversely across the rear end of said frame, laterally extending flights projecting from said belt, and an open unobstructed flight space formed in the rear end of said frame in registration with the transversely traveling linearly directed portion of said belt. 85

2. In a loading machine, a portable support, an elongated inclined frame pivotally mounted upon said support for horizontal sweep movement, an endless belt conveyor having its going and return ends disposed at similar elevations mounted upon said frame, flights projecting from said belt and movable through a material conveying way provided in said frame, a single sprocket provided at the forward or lower end of said frame, and a pair of sprockets provided at the upper or discharge end of said frame, said latter sprockets serving to provide for said belt a straight linear course of travel at the discharge end of said frame, said course of travel being transverse of said frame, and an open flight space formed in the discharge end of said frame in registration with the transversely traveling portion of said belt and across which base said flights freely travel. 100 105

In testimony whereof, I have signed my name to this specification.

NORTON A. NEWDICK.
